CLAIM

The ornamental design for a five-wheel display rack, as shown and described.

DESCRIPTION

FIG. 1 is a perspective view of the five-wheel display rack of the invention as seen from the front and above;

FIG. 2 is a perspective view of the five-wheel display rack of the invention as seen from the rear and above;

FIG. 3 is an enlarged left side elevational view of the five-wheel display rack of FIGS. 1 and 2, the right side elevational view being a mirror image thereof;

FIG. 4 is a top plan view of the five-wheel display rack of FIG. 3;

FIG. 5 is a bottom view of the five-wheel display rack of FIG. 3;

FIG. 6 is a front elevational view of the five-wheel display rack of FIG. 1 shown on a reduced scale; and,

FIG. 7 is a greatly enlarged fragmentary elevational view showing the pattern of decorative screen on the front panel of the five-wheel display rack encircled as 7 in FIG. 6, it being understood that the pattern repeats uniformly across the entire surface of the panel.
